UNITED STATES PATENT OFFICE.

GEORGE P. GARIN, OF BALTIMORE, MARYLAND.

DESIGN FOR A GAME CARD.

Application filed September 10, 1924. Serial No. 10,730. Term of patent 7 years.

To all whom it may concern:

Be it known that I, GEORGE P. GARIN, a citizen of the United States, residing at Baltimore, in the State of Maryland, have invented a new, original, and ornamental Design for Game Cards, of which the following is a specification, reference being had to the accompanying drawing, forming part thereof.

The figure is a plan view of a game card showing my new design.

I claim:

The ornamental design for a game card, as shown.

GEORGE P. GARIN.
